SAFETY SUPPORT FOR BRAKE RODS

Seth A. Crone, East Orange, N. J., assignor to
Buffalo Brake Beam Company, New York,
N. Y., a corporation of New York

Application August 1, 1934, Serial No. 737,881

3 Claims. (Cl. 188—210)

The present invention relates to safety supports for the connecting bottom rods of brake levers for the purpose of supporting the bottom rod in case it should tend to fall upon the track.

5 An object of the present invention is to provide such a safety support which is so constructed that it may be hung upon the brake beam and then positive pressure be given to the support or a sharp blow in order to deflect portions of the 10 safety support whereby to cause the support to be positively bound or rigidly attached to the brake beam. Other objects are to obtain efficient and simple construction.

These being among the objects of the present 15 invention the same consists of certain features of construction and combinations of parts to be hereinafter described and then claimed with reference to the accompanying drawing in which

Fig. 1 is a plan of parts of the brake mechanism 20 of a car truck showing the present improvements attached thereto;

Fig. 2 is an elevation of the safety support showing it applied to a beam, the bottom rod being in section;

Fig. 3 is a sectional elevation at right angles to Fig. 2, and

Fig. 4 is a view similar to Fig. 3, except that it shows the support as finally clinched or rigidly attached to the brake beam.

30 Referring to the drawing, the compression member 10 and the tension member 11 of the brake beam, which is but partially disclosed, may be of the usual construction. Mounted upon the brake beam so as to fulcrum thereon are the 35 brake levers 12, 13 which at their lower ends are secured together by the bottom connecting rod 14.

The improved brake beam attachment is preferably formed from a wrought metal bar and constitutes safety means for supporting the bottom 40 rod 14 in case it tends to fall on the track. The safety attachment comprises a stirrup or loop 15 forming the actual rod supporting member and is terminated by two parallel hooks, each comprising an upward leg 16, a cross piece 17 and a downward leg 18 at the outer end of the cross piece, so that each hook stands substantially at right angles to the plane of the stirrup or loop 15. The legs 16, 18 are also substantially parallel with each other.

50 The compression member 10 of the brake beam may be of the usual channel form so that the flanges thereof lie the one above the other. It will clearly be seen from Figs. 2 and 3 that the safety support or attachment is hung over the 55 compression member 10 so that the cross-connec-

tions 17 will extend across the top of the compression member. A slight recess 19 is formed at the inner angle between each cross connection 17 and downward leg 18, while another recess 20 is formed on the inner side of the lower end of each free leg 18.

When the safety support is hung in place the recess 19 will be opposite to the upper flange of the compression member, while the recess 20 will be opposite to the lower flange thereof as shown 10 in Fig. 3. To permit ready engagement of the safety support with the compression member, the lower ends of the legs 18 of the hooks are beveled at their inner sides at 22. So applied the improved safety hanger would be loose upon the 15 beam, but in order to insure its securement to the beam in a rigid manner a sufficiently sharp blow of a hammer directed upon the legs 18 at points between the flanges of the compression member 20 will cause a deflection at 23 of such portions of the legs 18, in some such manner as shown in Fig. 4. The result is that the legs 18 are driven into firm contact with the flanges of the compression member, the upper flange being received in the recesses 19, while the lower flange will be received 25 in the recesses 20.

It is apparent herefrom that a very simple construction of safety attachment may be resorted to and it is only necessary to impart sufficient blows thereto or pressure properly applied, in 30 order to intimately bind and attach the safety attachment to the brake beam so that it will not rattle in service. If the bottom connecting rod 14 should drop it will be supported by the stirrups or loops 15 of the safety attachments.

35

What I claim as new is:—

1. In a safety support for brake rods, the combination of a brake-beam channel member, and a bottom rod supporting member having a hook shaped member formed with two connected substantially parallel legs for engaging over the channel member, one leg being free, and the free leg extending downwardly past the two flanges of the channel and forcibly deflected between the flanges whereby to force it against the flanges 45 and rigidly secure it to the channel member.

2. In a safety support for brake rods, the combination of a brake-beam channel member, and a bottom rod supporting member of wrought metal, having a hook shaped member formed with two connected substantially parallel legs for engaging over the channel member, one leg being free, and the free leg extending downwardly past the two flanges of the channel and forcibly bent between the flanges whereby to force it against 50 55

the flanges and rigidly secure it to the channel member.

3. In a safety support for brake rods, the combination of a brake-beam channel member, and 5 a bottom rod supporting member having a hook shaped member formed with two connected substantially parallel legs for engaging over the

channel member, one leg being free, and having a recess at the inner side of its lower end and there engaging with the lower flange of the compression member, the free leg being forcibly deflected between the flanges to force the recessed end into firm engagement with the lower flange.

SETH A. CRONE.
